UNITED STATES PATENT OFFICE.

FRED J. WRIGHT AND DAVID E. HANSON, OF NEENAH, WISCONSIN.

RAIL-FASTENER FOR CEMENT TIES FOR RAILROADS.

No. 905,972.

Specification of Letters Patent.

Patented Dec. 8, 1908.

Application filed May 21, 1908. Serial No. 434,002.

To all whom it may concern:

Be it known that we, FRED J. WRIGHT and DAVID E. HANSON, citizens of the United States, and residing at Neenah, in the county 5 of Winnebago and State of Wisconsin, have invented a new and useful Rail-Fastener for Cement Ties for Use upon Railroads, of which the following is a specification.

Our invention relates to a chair for supporting the rail, to the manner of retaining the rail within the chair and to the manner of securing the chair upon the tie, and consists of a chair of peculiar construction, having bolt holes therein, spaced apart for receiving each a bolt, two bolt holes corresponding with those of the chair near each end of the tie, the pairs spaced apart the necessary distance for suiting the gage of the track, each of the bolt holes in the tie 10 being lined with a piece of pipe of a length equal to the thickness of the tie and of a bore adapted to receive the bolt to be used for securing the chair to the tie, said bolt being provided with the usual head and a 15 nut, the bolt being inserted from the lower side of the tie and provided with a washer of sufficient diameter for covering the end of said pipe and a large area of the tie around said pipe, and the objects of our invention 20 are, first, to provide a bolt hole through the tie which is adapted to receive a close fitting bolt, second, to provide a chair for supporting a rail which is adapted for being secured to a cement, or other mineral composition 25 tie, and our improvements are shown in the accompanying drawing, in which.

Figure 1 is a plan showing one end portion of a cement tie with our improved chair upon it. Fig. 2 is a longitudinal section vertically, of an end portion of a cement tie, showing its chair receiving bolt holes therein, and a side elevation of the chair bolted to the tie, and bolts and washers, a rail in section being held in position upon the chair. 40 Fig. 3 is a side elevation of a tie, upon a reduced scale, with the two rails of a track secured in position in the chairs and the chairs secured to the tie.

Similar numerals indicate like parts in 50 the several views.

1, indicates a tie, formed of cement or other plastic material, to which, as a plastic material tie, we make no claim, as they are not a new invention. At suitable distances 55 apart, holes for receiving bolts are formed in the making of the tie by inserting pieces of

tubing 3, and packing the material of the tie tightly around them while in a plastic state. These tubes should have such a diameter of bore as will permit the bolts to 60 pass through them easily, but with a close fit, and should be spaced apart for corresponding with the bolt holes 4 in the chairs 5, and also, for suiting the gage of the track. The chairs are to be formed of cast metal of 65 a suitable dimension and have a seat 6 for receiving a rail 7, by forming bosses, 8 and 9, one each side of the rail seat, the boss 8 having a groove 10, for receiving one flange 11, of the rail, and the boss 9, a dove tail 70 shaped groove 12, for receiving a keeper 13, the keeper extending out over the flange 14 of the rail, and serving the same purpose as the projecting lip 15, over the groove 10, that is, the keeper 13 and lip 15, serve to 75 retain the rail within its seat.

The keeper 13 consists of a flat surfaced rectangular piece of metal of a uniform thickness on longitudinal lines, one edge being thicker than the other and being adapted 80 to be inserted easily into the dove tail groove 12 by an endwise movement, and is retained therein by means of a spring, or cotter pin, 16, one outside of the boss at each end of the keeper. These keepers are to be placed, 85 preferably, outside of the rails. The chairs are secured in position by bolts 2, one at each end of the chair, each bolt having a large washer 17, under its head 18, the washer bearing on the tie around the tubing 90 and the bolts being provided with nuts 19, which may be a locking nut or have a pinch nut with it, and a washer 20, upon the upper side of the chair.

21, is a cushioning piece of wood, or other 95 non-metallic material, which is placed between the tie and chair for relieving the tie in a slight measure of the jar incident to the passage of a train of cars along the rails.

Having described our invention, what we 100 claim and desire to secure by Letters Patent, is,—

A rail fastener for a plastic material tie, consisting of the combination of the tie with a plurality of bolt holes adapted for the 105 passage of a bolt through the same formed through the tie by the insertion of a tube for each bolt hole, a rail, a chair, a seat in said chair for supporting the rail flange, a boss upon the chair each side of the rail, a groove 110 in one boss transversely of the chair adapted to receive one edge of the rail flange, a dove

tail shaped groove in the other boss, transversely of the chair outside of the other edge of the flange, a keeper adapted to fit said last named groove and to be inserted therein by sliding it endwise through said groove, a pin in each end of the keeper for its retention in its groove, said keeper extending from its boss toward the rail and over said last named flange edge, a bolt hole in each 10 end of the chair, a bolt passing through each of said bolt holes and through a tube lined bolt hole in the tie, a head upon each bolt

below the tie, a washer bearing upon a large area of surface of the tie around each bolt hole between a head and the tie, a nut upon each bolt for clamping the chair downward, and a non-metallic cushioning piece between the chair and tie.

FRED J. WRIGHT.
DAVID E. HANSON.
